DESIGN FOR A PERFUME BOTTLE

Elsa Schiaparelli, Paris, France, assignor to Societe Des Parfums Schiaparelli (Societe Anonyme), Paris, France, a corporation of France

Application June 21, 1939, Serial No. 85,604

Term of patent 14 years

To all whom it may concern:

Be it known that I, Elsa Schiaparelli, a citizen of the Republic of France, residing at Paris, France, have invented a new, original, and ornamental Design for a Perfume Bottle, of which the following is a specification, reference being had to the accompanying drawing, forming part thereof.

In the drawing

Fig. 1 is a front elevational view of a perfume bottle showing my new design.

Fig. 2 is a bottom view thereof.

Fig. 3 is a sectional view on line 3—3 of Fig. 2, the stopper being removed from the perfume bottle.

I claim—

The ornamental design for a perfume bottle, as shown and described.

ELSA SCHIAPARELLI.
